UNITED STATES PATENT OFFICE.

PIETRO STRAGIOTTI AND JOSEPH VERCCELLINI, OF HURLEY, WISCONSIN.

MUSIC-LEAF TURNER.

938,085.

Specification of Letters Patent. Patented Oct. 26, 1909.

Application filed August 13, 1908. Serial No. 448,448.

To all whom it may concern:

Be it known that we, PIETRO STRAGIOTTI and JOSEPH VERCCELLINI, subjects of Victor Emanuel III, King of Italy, residing at 5 Hurley, in the county of Iron and State of Wisconsin, have invented certain new and useful Improvements in Music-Leaf Turners; and we do declare the following to be 10 a full, clear, and exact description of the invention, such as will enable others skilled in the art to which it appertains to make and use the same, reference being had to the accompanying drawings, and to the figures of 15 reference marked thereon, which form a part of this specification.

Our invention relates to music leaf turners and has for its object to provide an apparatus for turning the leaves of a sheet of music or music book, which apparatus can 20 be applied to a piano, organ or the like, or a music stand which is designed and adapted to hold sheets or books of music in proper position in front of the musician.

With this object in view our invention 25 consists in the novel construction and arrangement of parts of our music leaf turner, and particularly in the construction and arrangement of the helix.

Our invention also consists in certain other 30 novel features of construction and in combinations of parts, all of which will be first fully described and afterward specifically pointed out in the appended claims.

Referring to the accompanying drawings: 35 Figure 1 is an elevation of the device showing same in operative position. Fig. 2 is a horizontal sectional view taken through line 2—2 of Fig. 1. Fig. 3 is a vertical sectional view taken through line 3—3 of Fig. 2. 40 Fig. 4 is fragmentary elevation showing the helix in position for turning the leaf. Fig. 5 is a horizontal sectional view taken through the operating mechanism. Fig. 6 is a front elevation of the operating pulley, and Fig. 7 45 is a rear elevation of the same.

Like numerals of reference indicate the same parts throughout the several figures in which;

1 indicates the device which comprises a 50 base 2, to which base is hinged two panels 3 and 4, said panels being hinged at 5 at their outer edges as clearly shown in Fig. 2.

Referring now to Fig. 1 and also to Fig. 3 55 it will be seen that each of the panels 3 and 4 is provided with a set screw 6 and 7 preferably located at the upper inner corner of

each of the panels 3 and 4, said screws 6 and 7 being for the purpose of regulating the distance of the panels 3 and 4 from the base 2.

Arranged, as shown in Fig. 2, and, between the two panels 3 and 4 is the music leaf turning apparatus 8, said apparatus comprising a helix 9, which helix is constructed of a steel wire with its spires or coils regular and sinistrorsal, said spires decreasing in their forward progression and ending with a bend 10 slightly outwardly curved, the projection of which on the normal plain of the helix is a spire of Archimedes. This apparatus is fixed as near as possible to the axis of rotation 11 of the music sheets 12, so that the final bend 10 of the helix passes over the said axis 11 of the music sheets. A shaft 13 carries said helix, said shaft extending rearwardly and carrying loosely thereon a pulley 14; a spiral spring 15 having one end 16 thereof connected to the pulley 14 and the other end 17 thereof connected to a partition 18 as shown in Figs. 2 and 6. Rigidly carried on the 80 shaft 13 in rear of the pulley 14 is a ratchet wheel 19, and a spring actuated pawl 20 carried on the rear face of the pulley 14 is normally in engagement with said ratchet wheel 19 as clearly shown in Fig. 7. The extreme 85 end of the shaft 13 carries a crank 21, to which crank is connected a spiral spring 22 as shown in Fig. 2 for the purpose of normally holding the crank 21 in position shown in Fig. 2. The sheets of music or book are 90 preferably held in position shown in Fig. 2 by means of a spring not shown.

Referring now to Figs. 1 and 4 it will be seen that in front of the first spire of the helix is arranged a half moon plate 23, said 95 half moon plate holding in place the first sheet to be turned as shown in Fig. 1; while the end of the bend 10 holds the last turned sheet in position as clearly shown in Fig. 1. A suitable cord or rope 24 is carried on the 100 pulley 14 and connects with the pedal or other suitable operating device, and upon depression of the pedal or other device the cord 24 rotates the pulley in a direction contrary to that of the hands of a watch as viewed from the front. The spring held pawl 20 on said pulley in engagement with the ratchet wheel 19 rotates said ratchet wheel, thus turning the shaft 13 and the helix 9. The leaves of a sheet of music or 110 book having been successively arranged between the spire of the helix as shown in Fig.

2 one revolution of the helix causes the bend
10 of the helix to engage one of the sheets,
said bend passing under the sheet to be
turned as shown in Fig. 4, and as said sheet
5 is turned by said bend each succeeding sheet
progresses one spire in the helix. When the
operating cord 24 is released the spiral spring
15 in front of the pulley 14 rotates said
pulley in the opposite direction again wind-
10 ing the operating cord 24 thereon; while the
coil spring 22 in engagement with the crank
21 on the shaft 13 draws said crank 21 into
position shown in Fig. 2 which rotates the
helix causing the bend 10 thereon to assume
15 the position shown in Fig. 1, thus maintain-
ing the turned sheet in its proper position;
while the moon-shaped plate 23 is passed up
in front of the next sheet to be turned as
shown in Fig. 1, thus securely maintaining
20 said sheet in proper position.

Having thus fully described our invention
what we claim as new and desire to secure by
Letters Patent of the United States, is;—

1. A music leaf turner comprising a spiral
25 having its coils regular and sinistrorsal, said
coils decreasing in their forward progression
and ending in an outwardly curved bend, a
plate carried in front of the first coil and in
rear of the said outwardly curved bend for
30 holding in place the first sheet to be turned,

the said outwardly curved bend holding in
place the last sheet turned, the said spiral
being adapted to receive a sheet of music
between each coil thereof, means for rotating
the spiral and means for automatically 35
maintaining the said outwardly curved bend
and the said plate in proper position for
holding the sheets of music against turning
after the spiral has been rotated.

2. A music leaf turner comprising a spiral 40
adapted to receive a sheet of music between
each coil thereof, said coils terminating in an
outwardly curved bend, a plate on said spiral
and in rear of said outwardly curved bend
for holding in place the next sheet to be 45
turned, said outwardly curved bend holding
in place the last sheet turned, means for
rotating the spiral, and further means for
maintaining the said outwardly curved bend
and the said plate in proper position for 50
holding the sheets of music against turning
after the spiral has been rotated.

In testimony whereof, we affix our signatures,
in presence of two witnesses.

PIETRO STRAGIOTTI.
JOSEPH VERCELLINI
